CATAMENIAL APPLIANCE

Donald R. Roberts, Plainfield, N.J., assignor to Personal Products Corporation, a corporation of New Jersey

Application April 19, 1956, Serial No. 579,345

5 Claims. (Cl. 128—289)

The present invention relates to new and useful improvements and structural refinements in catamenial napkins and in sanitary belts for maintaining such napkins in proper position during use.

At the present time, the most common form of sanitary pad or napkin commercially available for use by women is a generally oblong, arcuate-ended pad of absorbent material enclosed within an external textile cover or wrapper. This wrapper is normally made considerably longer than the enclosed absorbent pad and provides two end extensions for attaching the napkin to a waist-encircling sanitary belt or other garment to maintain it in proper position during use.

Such a construction provides a hammock-like, two-point suspension for the napkin, which configuration is objectionable for several reasons. Such a suspension tends to roll and shift back and forth during use as a result of bodily movements and to become distorted and deformed particularly when wetted, whereby comfort is quickly lost along with security and protection against fluid leakage or spillage over the sides thereof. Rubbing and chafing also occur from such bodily movements whereby actual discomfort and distress are often created.

Efforts to avoid such an undesirable situation have been directed, for example, to the use of larger and more bulky sanitary devices. Other attempts utilized greater tensions on the presently used napkins by securing them in position more tightly. These variations have not worked out well but have only aggravated the irritation and discomfort.

Three-point suspension sanitary devices also have been considered hitherto but have been found unsatisfactory for various reasons, primarily discomfort, chafing and lack of security. As a result, there still remains considerable room for improvement in this art.

It is therefore a principal object of the present invention to provide a catamenial napkin and a sanitary belt therefor which will not tend to roll or shift back and forth due to bodily movement during use and which will not become distorted or deformed when wetted. It is a further principal object of the present invention to provide a catamenial napkin which will continually exert slight pressures along the lines of both inner thighs rather than in a single centrally positioned line to effectively prevent any fluid leakage or spillage over the sides thereof.

Such objects are accomplished by providing a relatively flat, somewhat flared or pear-shaped catamenial napkin comprising an external cover, an absorbent pad and a soft inner face, said napkin being provided with two forwardly-extending fastening strips and one rearwardly-extending fastening strip for attachment to a sanitary belt which correspondingly has two forwardly-positioned attaching tabs and one rearwardly-positioned attaching tab. The strips are of sufficient length that the points of attachment between the strips and tabs are spaced from the main absorbent pad portion of the napkin. Additionally, fastening devices are provided on

2

the belt tabs to effect attachment of the strips thereto in such a way that free relative pivotal movement is permitted between the strips and the tabs. Moreover, the thickness of the absorbent pad varies from a relatively thick portion at the rear part thereof to a relatively thin portion at the front part thereof to provide a better anatomical fit.

Other objects and their accomplishment will become apparent from the following description of the invention taken in conjunction with the accompanying drawings wherein:

Fig. 1 is a front perspective view of the improved sanitary belt;

Fig. 2 is a rear perspective view of the improved sanitary belt;

Fig. 3 is a plan view of the improved sanitary napkin;

Fig. 4 is a side elevational view of the improved sanitary napkin; and

Fig. 5 is a perspective view of the combination of the sanitary napkin and the sanitary belt.

Referring now to the drawings in detail, the improved sanitary device comprises, as one principal component thereof, a sanitary belt 10 comprising a resilient or elastic waist-encircling band 11 to which are attached two front attaching tabs 12 and 13 in spaced relationship by stitching 14 and 15. The points of attachment of the tabs are spaced apart a distance of from about 5 to about 7 inches, and preferably about 6 inches, in the case of a belt 20 designed for a 22 to 34 inch waist. A rear resilient loop or elastic strap 16 is provided and is secured to the rear portion of the band 11 at spaced positions by stitching 17 and 18. Again, the points of attachment are spaced apart a distance of from about 5 to about 7 inches, and preferably about 6 inches, in the case of a belt designed for a 22 to 34 inch waist. A rear attaching tab 19 is suspended from approximately the central portion of the rear strap 16 and is secured thereto as by stitching 20. Fastening devices 21, 22 and 23 are provided, one on each tab respectively, for attachment purposes as will be more fully described hereinafter. The angle α in Figs. 1 and 2 between the tabs and the band 11 is shown as about 45° but this angle may be varied from about 30° to about 60° and preferably from about 40° to about 50°.

The second principal component of the improved sanitary device is a sanitary napkin 30, the main body of which, as noted in Figs. 3 and 4, has a relatively flat, somewhat flared or pear-shaped outline. The main body of the napkin 30 comprises an externally positioned outer cover 31 which is either water-repellent or water-resistant, *per se*, or which is rubberized, latex-treated, or otherwise coated or impregnated with a thermoplastic or thermosetting material to prevent the passage of fluids therethrough and to heat seal the component parts.

The external cover 31 is provided with two forwardly-extending fastening strips 33 and 34 at the base or wider portion thereof and a rearwardly-extending fastening strip 35 at the apex or narrower portion thereof. Each strip is provided with openings which are shown at 35, 35 in the rear strip and at 36, 37, 38 and 39 in the front strips.

Any number or any combination of numbers of these openings can be provided. These openings cooperate with the previously-described fastening devices 21, 22, and 23 whereby the sanitary napkin can be adjustably positioned for proper use. As noted in Figs. 1 and 2, the attaching device 23 has a curved, metallic clasp having a centrally positioned loop 23a which is adapted to receive the openings and to permit relatively free pivotal movement thereof. It is to be appreciated that substantially any type of fastening device may be employed provided it is capable of permitting a relatively free pivotal movement between the strip and the tab.

A loosely-compacted, highly absorbent pad 40 is positioned on the main portion of the sanitary napkin and takes the same outline generally as the main portion of the external cover 31. The absorbent pad 40 may be made of carded cotton webs, air-laid cellulosic fibrous webs, comminuted wood pulp bats, or like absorbent materials. As illustrated, the absorbent pad is relatively thick at the rear portion thereof and tapers down to relative thinness at the front portion whereby a better anatomical fitting is obtained. This difference in thickness may be obtained by building up the desired portions by adding more layers of an absorbent web. Alternatively, the shape could be obtained by molding or by using special fiber air-laying devices, etc. As shown, the rear portion is approximately three-eighths of an inch thick and the front portion is less than one-eighth but such is merely illustrative and is not to be construed as limitative of the invention. An inner facing 41 is positioned over the absorbent pad 40 and extends beyond its edges to be secured to the edges of the outer cover 31 whereby an enclosing envelope is formed for the absorbent pad 40. The inner facing is of a soft and absorbent nature particularly suited for contacting the body and is preferably of a nonwoven nature, a napped or brushed fabric, or a similar material. If desired, the inner facing 41 may be omitted and a light coating of a water-resistant polymeric material or resin sprayed or otherwise applied to the absorbent pad to stabilize it in the proper position and prevent fiber shifting, dusting, and the like.

Fig. 5 illustrates, in perspective, the appearance of the sanitary napkin and the sanitary belt in attached position, such as would be worn in use.

It is to be noted that the lengths of the front fastening strips 33, 34 are such that the points of attachment of the napkin to the belt are spaced from the absorbent pad so that any strains or stresses caused by bodily movements of the user are taken up in these strips and not transmitted or transferred further. This strip length cooperates with the angularity of the attachment tabs on the sanitary belt whereby the line of the tab and strip substantially follows the inguinal angle on the body which basically is the angle formed between the torso and the upper inner thighs. In this way, the slight pressures exerted by the napkin are exerted along both outer edges thereof adjacent the thighs whereby a pocket-like suspension is formed having a U-shaped napkin cross-section rather than a hammock suspension having an inverted U-shaped napkin cross-section. This suspension, cooperating as it does with the slight pressures exerted against the thighs effectively minimizes the hazards of fluid leakage and side-spillage and decreases the rubbing or chafing by the napkin. As a consequence, smaller, more compact and less bulky sanitary devices are made possible without loss in security or protection.

The improved catamenial napkin and sanitary belt was evaluated along other types of sanitary devices having two-point suspension systems by actual use by test panels of several women for each type of napkin. It was determined that the stain pattern of the napkins using two suspension point systems were very large, particularly in the front-to-rear direction, and that there were occasional failures due to spillage or leakage at the sides. In the improved anatomical-fitting, three-point suspension napkin of the present invention, the stain pattern was much smaller, thus indicating less shifting or rolling of the napkin and there were no failures due to spillage or leakage at the sides.

If desired, the apex or narrower portion of the main body of the napkin may be widened slightly and provided with a pair of fastening strips for attachment to a pair of tabs secured to the waist-encircling band. Such would eliminate the need for a rear strap inasmuch as the napkin fastening strips would be secured directly to the belt tabs.

Other variations and modifications may be made within

the scope of this invention and portions of the improvements may be used without others.

While I have shown and described what is believed to be a preferred embodiment of my invention in the matter of simplicity and durability of construction, ease of utilization, etc., it will be apparent that the details of such construction may be more or less modified within the scope of the claims without departure from the principles of construction or material sacrifice of the advantages of the preferred design.

I claim:

1. A catamenial napkin comprising a relatively flat, flared, water-repellent external cover, a loosely compacted pad of highly absorbent material on said cover, an inner facing of soft absorbent material covering said pad, a pair of forwardly-extending fastening strips at the wider portion of said cover and a rearwardly-extending fastening strip at the narrower portion of said cover for attachment to a sanitary belt comprising a pair of front tabs for attachment to the forwardly-extending strips of the napkin and a rear tab for attachment to the rearwardly-extending strip of the napkin, said front tabs being so spaced apart on said band and so angularly positioned thereon as to cause the forwardly-extending strips, when attached thereto, to follow the inguinal angle on the body of the wearer, said strips having a length such that the attachment of the napkin to the belt are at points spaced from the external cover, the absorbent pad and the inner facing whereby movement thereof due to bodily movements is minimized, said pad having a portion of relative thickness at the rear part thereof and a portion of relative thinness at the front part thereof whereby a better anatomical fitting is obtained.

2. A catamenial appliance comprising in combination, a disposable catamenial napkin comprising a relatively flat, flared, water repellent external cover, a loosely compacted pad of highly absorbent material having an inner facing of soft absorbent material, said cover and said inner facing extending beyond the periphery of said pad to form marginal portions, said cover and said facing being joined at said marginal portions, a pair of forwardly extending strips at the wider portion of said cover and a rearwardly extending strip at the narrow portion of said cover, and a sanitary belt comprising a resilient, waist encircling band, a pair of front tabs on said band for attachment to the forwardly extending strips of the napkin, a rear tab on said band for attachment to the rearwardly extending strip of said napkin, the front tabs on said band being so spaced apart on said band and so angularly positioned thereon and the forwardly extending strips on said napkin being so angularly positioned with respect to said napkin as to cause said front tabs and said forwardly extending strips to follow the inguinal angle on the body of the wearer when said appliance is worn, and fastening devices on said tabs for effecting attachment of said strips thereto.

3. A catamenial appliance comprising in combination, a disposable catamenial napkin comprising a relatively flat, flared, water repellent external cover, a loosely compacted pad of highly absorbent material having an inner facing of soft absorbent material, said cover and said inner facing extending beyond the periphery of said pad to form marginal portions, said cover and said facing being joined at said marginal portions, a pair of forwardly extending strips at the wider portion of said cover and a rearwardly extending strip at the narrow portion of said cover, and a sanitary belt comprising a resilient, waist encircling band, a pair of front tabs on said band for attachment to the forwardly extending strips of the napkin, a rear tab on said band for attachment to the rearwardly extending strip of said napkin, the front tabs on said band being so spaced apart on said band and so angularly positioned thereon and the forwardly extending strips on said napkin being so angularly positioned with respect to said napkin as to cause said front tabs and said forwardly

extending strips to follow the inguinal angle on the body of the wearer when said appliance is worn, and fastening devices on said tabs for effecting attachment of said strips thereto at points spaced from the cover, pad and facing of said napkin.

4. A catamenial appliance comprising in combination, a disposable catamenial napkin comprising a relatively flat, flared, repellent external cover, a loosely compacted pad of highly absorbent material having an inner facing of soft absorbent material, said cover and said inner facing extending beyond the periphery of said pad to form marginal portions, said cover and said facing being joined at said marginal portions, a pair of forwardly extending strips at the wider portion of said cover and a rearwardly extending strip at the narrow portion of said cover, and a sanitary belt comprising a resilient, waist encircling band, a pair of front tabs on said band for attachment to the forwardly extending strips of the napkin, a rear tab on said band for attachment to the rearwardly extending strip of said napkin, the front tabs on said band being so spaced apart on said band and so angularly positioned thereon, and the forwardly extending strips on said napkin being so angularly positioned with respect to said napkin as to cause said front tabs and said forwardly extending strips to follow the inguinal angle on the body of the wearer when said appliance is worn, and fastening devices on said tabs for effecting attachment of said strips thereto, said devices being capable of providing relative pivotal movement between the strips and the tabs.

5. A disposable catamenial napkin comprising a rela- 80

tively flat, flared, water repellent external cover, a loosely compacted pad of highly absorbent material, an inner facing of soft absorbent material covering said pad, said cover and said inner facing extending beyond the periphery of said pad to form marginal portions, said cover and said facing being joined at said marginal portions, a pair of forwardly extending strips at the wider portion of said cover and a rearwardly extending strip at the narrow portion of said cover, said forwardly extending strips being so angularly positioned with respect to said napkin as to follow the inguinal angle on the body of the wearer when said napkin is worn attached to a sanitary belt having a resilient, waist encircling band, a pair of front tabs on said band for attachment to the forwardly extending strips of the napkin, a rear tab on said band for attachment to the rearwardly extending strip of said napkin, the front tabs on said band being so spaced apart on said band and so angularly positioned thereon as to follow the inguinal angle on the body of the wearer.
